MEANS FOR ADJUSTABLY SUSPENDING POWER TOOLS OVER TABLE TOPS

William L. Davis, Fort Bragg, Calif.

Application October 13, 1951, Serial No. 251,233

6 Claims. (Cl. 143—6)

The present invention relates to suspension means for a power tool, and has particular reference to suspension means for a rotary power saw over a table top with freedom of various adjustments.

More particularly it is proposed to provide a yoke frame adapted for mounting on a table top having a shaft supported transversely in the center thereof, with means for adjusting the shaft support with respect to the frame and the shaft with respect to the support.

It is further proposed to use the end of the shaft for supporting the vertical member, with means for adjusting the vertical member vertically and angularly with respect to the table top and means for locking the said member in adjusted position.

Another object of my invention is to provide a gauge readable against the end of the shaft for determining the height of a suspended tool with respect to the table top and the angularity of the tool with respect to a straight edge on the table top.

A still further object of my invention is to use the said member as a support for a horizontally presented rail which partakes of the adjustments of the said member.

It is further proposed to provide a carriage on said rail, the carriage having the tool suspended therefrom and being free to ride in the rail for sawing operations.

It is additionally contemplated to provide means whereby the rail may be tilted transversely with respect to the supporting member to bring the saw into a desired angularity with respect to the plane of the table top to cut through the wood or other work at a desired angle, and to provide accurate means for effecting the adjustments and means for locking the rail in adjusted position.

Further objects and advantages of my invention will appear as the specification proceeds.

The preferred form of my invention is illustrated in the accompanying drawing, forming part of this application, in which:

Figure 1 shows an end view of my suspension means, looking at it from the rear of the table;

Figure 2, a side view of the same;

Figure 3, a plan view of the same;

Figure 4, an enlarged detail section taken along line 4—4 of Figure 2;

Figure 5, a detail view in plan of a straight-edge used in connection with my invention; and

Figure 6, a side view of the same.

While I have shown only the preferred form of the invention, it should be understood that various changes or modifications may be made within the scope of the claims attached hereto without departing from the spirit of the invention.

Referring to the drawing in detail, my invention comprises in its principal features, a yoke-shaped frame 1 adapted for mounting upon a table top 2, a cross 3 mounted in the frame, a shaft 4 slidable transversely in the cross, a worm 5 suspended from the shaft, a rail 6 carried by the worm, a carriage 7 slidable in the rail and a tool support 8 suspended from the carriage.

The frame 1 is here shown as being arcuate and comprising two standards having bottom flanges 9 adapted for fastening to a table top and curving toward one another to terminate in aligned horizontal stretches joined centrally by the cross 3, the latter being held to the ends of the standards by means of nuts 10, which allows of a certain amount of adjustment of the cross with re-

spect to the standards, by backing one of the nuts and advancing the other.

The cross-arms of the cross have the shaft 4 slidably mounted therein, the shaft being held against turning movement by means of a set screw 11 engaging in a lengthwise groove 12 of the shaft, which latter set-screw may also be used to lock the shaft against endwise motion.

The end of the shaft is flattened at the top and the bottom to present flat top and bottom surfaces 13 and 14 and is formed with a central vertical hole in which the worm 5 is slidably received, the worm being locked in any desired position by means of two nuts 15 and 16, the upper one of which has a handle 17 projecting therefrom. The worm may be raised and lowered by backing one of the nuts and advancing the opposite nut and may be locked in adjusted position by tightening the nuts upon the shaft. It will be noted that as long as the nuts are not tightened, the worm is free to revolve in the shaft, without changing the elevation.

The bottom end of the worm carries a head 18 which is split horizontally to present two sections 19 and 20, the section 19 being fixed to the worm, and the section 20 being hinged to the section 19, as at 21.

The lower section has the rail 6 permanently and fixedly secured upon the lower face thereof. The rail is disposed horizontally and preferably comprises two channels 22 arranged back to back in spaced relation by suitable spacing members indicated at 23. The confronting faces of the channels are formed with upper and lower tracks 24, and a four-wheel carriage 25 is movable between the tracks, the carriage comprising a pair of spaced axles 26 and bearing wheels adapted to ride between the tracks.

The wheels are made of sufficient size to contact both upper and lower tracks, so as to prevent tilting longitudinally and to come close to the channels to guard against lateral tilting with respect to the channels. The carriage also includes the supporting member 8 suspended from the axles which latter has the tool housing 27 rigidly secured thereto.

The supporting member preferably is in the form of a flat plate set on edge and of sufficient width to be in sliding contact with the sides of the lower tracks 24 so that the latter may serve to steady the carriage when the rail as a whole is tilted on the hinge 21. The supporting plate is not intended to extend into the space between the upper tracks, because the carriage is supposed to carry the main part of the load at any desired angularity.

The lower section 20 is held to the upper section by means of a side plate 28 secured upon the upper section by means of a screw 29 and upon the lower section by means of a screw 30. As long as both screws are screwed tightly, the sections are rigidly connected. But the upper section is formed with a slot 31, the walls of which engage over the screw 29, and if the two screws are loosened, the slot walls ride along the screw 29 and allow the lower section to drop, on its hinge, to any desired angularity, to be held again in adjusted position by tightening of the screws. Notches 32 may be provided in the upper edge of the plate 28 for reading against the upper surface of the upper section to indicate the angle of the lower section, the upper edge of the plate being preferably made cam-shaped, as shown.

The outer edge of the upper section 19 of the worm head has a gauge 33 projecting upwardly therefrom to read against the upper surface of the shaft 4. When the top of the gauge is on a level with the said upper surface, this may be made an indication that the cutting edge of the saw shown at 34 is disposed immediately adjacent the top of the table. As the worm is raised, the scale on the gauge indicates the height of the saw above the table surface. The gauge 33 is pivoted to the section 19 as at 33', so that it may be swung downward into an out-of-the-way position.

The upper face 13 of the shaft is also calibrated, as at 35, to indicate the angle of the rail with respect to the table edge or a straight edge disposed on the table, these calibrations being also readable against the gauge 33.

A suitable auxiliary means may be provided for ac-

curately adjusting the lower head section 20 to a desired angularity, in the form of a turn-buckle 36 securable to the rail, as at 37, and to a bracket 38 mounted upon one of the standards with freedom of vertical and angular adjustability, the bracket being held in adjusted position by the set screw 39.

A suitable straight-edge particularly adapted for use in connection with my invention is shown as comprising a T-square 40 of a length slightly in excess of the width of the table top and having a head 41 at one end and a link 42 at the other end, the link being adapted to be drawn upon the table edge opposite the head by means of a wire 43 and a lever 44 which firmly holds the T-square in rectangular position when the lever and the wire reach dead-center position.

The advantages of my suspension means will be apparent from the foregoing description. The suspension means may be perfectly balanced with respect to the main frame 1 by adjustment of the nuts 10. The shaft 4 is adjustable cross-wise of the main frame to bring the worm 5 relatively close to the main frame or a considerable distance away from the frame. It is even possible to project the worm 5 to a position outside the table top, if it is desired to work on a piece of wood which is more conveniently mounted on some other support.

The height of the saw blade may be readily and accurately adjusted by suitable operation of the nuts 15 and 16, and while this adjustment is being made the saw blade may swing into a desired angular position with respect to the straight-edge, both the height and angular position being readily discernible by reading the gauge 33 against the top face 13 of the shaft and the angular scale thereon.

The angle of the saw blade with respect to the table top may be readily adjusted by operation of the plate 28 and the exact angle ascertained by reading the notches on the plate against the head section 19.

When the rail is adjusted to angular position, the four-wheel carriage bearing against both upper and lower tracks will maintain the tool in the plane to which it has been adjusted, without interfering with the operation of the saw.

I claim:

1. In combination, a shaft, means for horizontally supporting the same over a table top, a worm slideable and revolvable in the shaft, a pair of nuts on the worm and cooperable with the shaft for locking the worm to the shaft, a head at the lower end of the worm split horizontally to present an upper and a lower section, a hinged connection between the sections allowing the lower section to swing downwardly, means for locking the lower section in adjusted position, and a guide rail secured upon the lower section.

2. In combination, a shaft, means for horizontally supporting the same over a table top, a worm slideable and revolvable in the shaft, a pair of nuts on the worm and cooperable with the shaft for locking the worm to the shaft, a head at the lower end of the worm split horizontally to present an upper and a lower section, a hinged connection between the sections allowing the lower section to swing downwardly, means for locking the lower section in adjusted position, and a guide rail secured upon the lower section, the guide rail having a carriage movable thereon, and the carriage having a tool housing suspended therefrom.

3. In combination, a shaft, means for horizontally supporting the same over a table top, a vertical mem-

ber carried by said shaft, a head at the lower end of the member split horizontally to present an upper and a lower section, a hinged connection between the sections allowing the lower section to swing downwardly, means for locking the lower section in adjusted position, and a guide rail secured upon the lower section so as to present a track clear from end to end.

4. In combination, a shaft, means for horizontally supporting the same over a table top, a vertical member carried by the shaft, a head at the lower end of the member split horizontally to present an upper and a lower section, a hinged connection between the sections allowing the lower section to swing downwardly, means for locking the lower section in adjusted position, and a guide rail secured upon the lower section so as to present a track clear from end to end, the locking means comprising a plate positioned adjacent the two sections and screws for securing the plate upon the two sections, and the plate having a slot adapted for riding on one of the screws when the screws are loosened.

5. In combination, a yoke adapted for mounting on a table top and having spaced legs and a bridging member connecting the upper ends thereof, a shaft mounted horizontally in the bridging member and transversely to the latter and having an end projecting beyond the yoke, a member suspended from the said end, a guide rail supported horizontally by the said member and having an end extending through the yoke, and a carriage slidably supported by the guide rail and operable within the confines of the yoke, the guide rail being hinged to the suspended member for angular adjustment and having means for locking the same upon adjustment.

6. In combination, a yoke adapted for mounting on a table top and having spaced legs and a bridging member connecting the upper ends thereof, a shaft mounted horizontally in the bridging member and transversely to the latter and having an end projecting beyond the yoke, a member suspended from the said end, a guide rail supported horizontally by the said member and having an end extending through the yoke, and a carriage slidably supported by the guide rail and operable within the confines of the yoke, the guide rail being hinged to the suspended member for angular adjustment and having means for locking the same upon adjustment, and the guide rail and the carriage having closely fitting cooperative means for holding the carriage against tilting motion with respect to the rail.
